UNITED STATES PATENT OFFICE.

JOHN R. DEAN, OF WALLINGFORD, CONNECTICUT, ASSIGNOR TO INTERNATIONAL SILVER CO., OF MERIDEN, CONNECTICUT, A CORPORATION OF NEW JERSEY.

DESIGN FOR A SPOON, FORK, OR SIMILAR ARTICLE.

40,599.

Specification for Design.

Patented Apr. 5, 1910.

Application filed February 7, 1910. Serial No. 542,653. Term of patent 7 years.

To all whom it may concern:

Be it known that I, JOHN R. DEAN, a citizen of the United States, residing at Wallingford, in the county of New Haven and State of Connecticut, have invented a new, original, and ornamental Design for a Spoon, Fork, or Similar Article; and I do hereby declare the accompanying drawing to be a full, clear, and exact illustration of the same, and which said drawing constitutes

part of this specification, and represents a face view of a spoon, fork or similar article embodying my design.

Claim.

The ornamental design for a spoon, fork or similar article, as shown.

JNO. R. DEAN.
